UNITED STATES PATENT OFFICE.

ELBERT L. HYDE, OF PITTSBURGH, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,210,170.

Specification of Letters Patent. Patented Dec. 26, 1916.

Application filed July 21, 1914. Serial No. 852,257.

To all whom it may concern:

Be it known that I, ELBERT L. HYDE, a resident of Pittsburgh, in the county of Allegheny and State of Pennsylvania, have 5 invented a new and useful Improvement in Garment-Stays, of which the following is a specification.

This invention relates to garment stays and particularly to wire stays for use in corsets or other like articles of wearing apparel.

The object of the invention is to provide a simple stay which can be readily manufactured, which is flexible and resilient, 15 which yields readily in all directions, which includes a long length of wire in a stay of given dimensions, and which is reinforced along its edges so that it is not liable to take a permanent set when subjected to 20 short bends, and also distributes the wear over a long length of wire.

The invention comprises the stay herein-after described and claimed.

In the drawings Figure 1 represents a 25 face view of one form of stay embodying the invention; Fig. 2 is an edge view thereof; and Fig. 3 is a view corresponding to Fig. 2 and illustrating a modification.

The stay shown in the drawings is formed 30 of wire and in the embodiments illustrated is formed of a single wire 1 which is bent back and forth across the stay from edge to edge thereof and preferably along diagonal lines to form a series of loops or 35 eyes 2 lying along the edges of the stay and connected by diagonally extending portions or crossings 3. The diagonal arrangement of the crossings brings the loops or eyes 2 along opposite edges of the stay substantially 40 opposite each other. Said loops all extend longitudinally toward the ends of the stay, and preferably, although not necessarily, each loop overlaps the next adjacent crossing portion of the wire as indicated at 5. Said extensions may also be 45 somewhat returned upon the main portions of the loops so that they project inwardly toward the center line of the stay, although this is not necessary. Each loop has a 50 rounded or arched outer portion 4, which portions of the wire form comparatively smooth edges of the stay and prevent it from wearing through the stay pocket in which it is placed, which might occur if the 55 edges of the stay included sharp or angular

bends or kinks in the wire as in some forms of stay. The loops along opposite edges of the stay point in opposite directions. In other words, the loops along one edge of the stay point toward one end thereof, while 60 those along the other edge of the stay point toward the other end thereof. These loops may point toward either end of the stay, so long as they point in opposite directions. Fig. 1 illustrates an arrangement in which 65 the loops are disposed at an obtuse angle to the diagonally extending crossings 3, while Fig. 3 shows an arrangement in which the loops point in the other direction, and form an acute angle with the diagonally extending portions or crossings. Either arrangement 70 is satisfactory, although the form shown in Fig. 1 may be manufactured more readily and the bends in the wire are not so sharp as in the other form.

In both forms of the invention described each loop of the wire is connected to two loops on the opposite edge of the stay by two crossing portions of the wire, to wit, a long crossing 3 and a shorter crossing 6, 80 all of said crossings being substantially straight from loop to loop and lying parallel to each other and at an angle to an outer transverse line across the stay. This arrangement enables the stay to be readily 85 manufactured by simple operations, and also increases its life, due to the fact that the wires do not cross or interlock with each other, excepting only where successive loops overlap and mutually brace each other.

The stay described is simple and includes a long length of wire in a stay of given dimensions. It is reinforced along its edges by the overlapping of the loops upon adjacent crossings which increases the resilience 90 of the stay and its ability to resist bending strains, particularly in the flatwise direction.

What I claim is:—

1. A garment stay, comprising wire bent 100 back and forth from edge to edge of the stay along diagonal lines to form a series of longitudinally extending loops or eyes lying along the edges of the stay and connected by straight parallel diagonally extending crossings, the loops or eyes along opposite edges of the stay extending toward the opposite ends thereof and overlapping 105 the next adjacent crossing portions of the wire.

2. A garment stay, comprising wire bent back and forth from edge to edge of the stay to form a series of longitudinally extending loops or eyes lying along the edges of the stay and connected by straight parallel diagonally extending crossings, the loops or eyes along opposite edges of the stay being substantially opposite each other

and extending in opposite directions longitudinally of the stay. ¹⁰

In testimony whereof I have hereunto set my hand.

ELBERT L. HYDE.
